UNITED STATES PATENT OFFICE.

JOHN T. JANETTE, OF CHICAGO, ILLINOIS.

MOTOR-CONTROLLING DEVICE.

1,033,900.

Specification of Letters Patent. Patented July 30, 1912.

Application filed November 7, 1910. Serial No. 590,968.

To all whom it may concern:

Be it known that I, JOHN T. JANETTE, a citizen of the United States, residing at Chicago, county of Cook, and State of Illinois, have invented new and useful Improvements in Motor-Controlling Devices, of which the following is a specification.

My invention relates to improvements in controlling devices for motors, with especial reference to that class of devices which are employed for automatically starting and stopping an electric motor connected with air pumping mechanism, whereby a desired air pressure in the delivery or service pipe connections may be uniformly maintained.

The object of my invention is to provide a form of controlling apparatus which will be actuated in part by the air itself when the predetermined pressure is attained, and in part by an independent positive movement or free throw, adapted to separate the electrical connections with a quick positive stroke independently of the slower movements caused by the gradually increasing pressure of the air.

In the following description, reference is had to the accompanying drawings, in which—

Figure 1 is a side view, part in section, of an air pumping mechanism embodying my invention, the part in section being drawn to a plane exposing one side of the controlling apparatus. Fig. 2 is a plan view of the same with the air pumps illustrated in horizontal or cross section, and the motor, together with the connections for driving the pump pistons, removed.

Like parts are identified by the same reference characters in both views.

The motor A and pump cylinder B are preferably mounted upon the same base C. In the construction illustrated, two pumping cylinders B are employed, and the pistons b therein are driven from the motor 45 through a shaft a and suitable gearing located in the casing a' (a worm and worm wheel being preferably used), whereby a crank shaft B' is rotated and its motion transmitted to the respective pistons through 50 the connecting rods B''. These parts may be of any ordinary construction.

The air compressed in the pump cylinders B is delivered through depending pipe connections D, d, and d', to any suitable point 55 of discharge or use, or to a storage tank, a valve D' being preferably employed in

the pipe connections d' to prevent a return of air to the pump cylinders. A diaphragm chamber E, provided with a partition diaphragm e, is connected below the diaphragm with the air supply connections. In the construction illustrated, the pipe e' serves as a means of communication between the pipe d' beyond the valve D' and the chamber E. The diaphragm e is flexible, and it is therefore obvious that as the pressure increases in the pipe d' and in the diaphragm chamber below the diaphragm e, said diaphragm will be lifted with increasing upward pressure proportioned to the pressure of the air.

The upward movement of the diaphragm e, above described, is used to control the operation of a switch bar F, which in turn controls the circuit of the electric motor A, 75 said switch bar F being provided with downwardly extending contact arms f at each end, adapted to pass between resilient terminals, comprising upwardly projecting lips f' mounted upon the base C and electrically connected with the current conductors G which supply current to the motor A from any suitable source of electrical energy.

The switch bar F is provided with a rearwardly extending arm H, which is rigidly connected with a lever I pivotally supported from the base or bed at I'. When the diaphragm e is raised by the pressure of the motor delivered air as above explained, the upward movement of said diaphragm e is transmitted through a post J, mounted upon the diaphragm, to a lever K, to one arm of which said post is pivoted at k. The lever is pivoted at k' to a fulcrum link post L 95 supported from any suitable part of the frame or base, preferably from the casing of the diaphragm chamber E. This lever K is provided with a depending foot piece M, adapted to engage one arm of the lever I in the rear of the connection between said lever I and the arm H, in the construction as illustrated in the drawings. Said lever K is also provided with a swinging switch actuating member N. Said member N is pivoted to the lever K and is provided with an anti-friction roller N', adapted to bear normally upon an angular face n at the extremity of the lever I which is nearest the switch bar F. A spring O connects the lever N with the lever K in such a manner as to hold the roller N' forcibly against

2
said angular face *n* of the lever *I*. When the diaphragm *e* is lifted by the air pressure in the lower part of the diaphragm chamber, the actuating member *N* moves downwardly until the roller passes the extremity *i* of the lever *I* and engages upon the angular under surface *n'* of said lever, whereupon the pressure of the roller *N'* of the actuating member *N*, will be exerted upon 10 the angular face *n'* and will tend to lift this arm of the lever *I*, thereby also lifting the switch bar *F* out of contact with the terminals *f'*. This lifting pressure is produced by the reaction of the spring *O* and therefore, as soon as the switch bar *F* commences to move, the pull exerted by said spring *O* will cause it to lift with a quick positive stroke in a manner to prevent destructive arcing between the contacts *f* and terminals *f'*.

20 It is desirable that the engagement of the contact arms *f* with the terminals *f'* shall be a forcible engagement, and the terminal lips *f'* are therefore formed of resilient material capable of exerting considerable frictional pressure upon the contact arms *f*. For this reason the spring *O* cannot be made of sufficient strength to insure the lifting of the switch bar *F* under all 25 conditions without having said spring *O* of such strength as to require considerable power to force the roller *N'* past the lever extremity *i*. For this reason the foot piece *M* is provided, and a spring *O* of comparatively light weight is used. The parts are 30 so proportioned, that as soon as the roller *N'* passes below the lever extremity *i*, the foot piece *M* will come in contact with the other arm of the lever *I* beyond the pivot 35 40 *I'* and thus exert a direct downward pressure upon this arm of the lever *I*, whereby the initial upward movement of the switch bar *F* may be easily produced. This movement will continue until the contact arms *f* 45 of the switch bar *F* are sufficiently released to permit them to be thrown upwardly by a quick positive stroke caused by the reaction of spring *O*.

50 A spring *S* is coiled around the post *J* and interposed between the diaphragm *E* and a socketed member *T*, having threaded connection with the diaphragm casing in an aperture through which said post *J* extends. When the pressure in the diaphragm chamber *E* below the diaphragm *e* falls below the desired or predetermined 55 limit, the reaction of spring *S* forces the diaphragm *e* downwardly and draws the short end of lever *K* downwardly, whereupon the member *N* moves upwardly until the roller *N'* passes above the extremity *i* of the lever *I* and bears upon the angular face *n* of said lever *I*. In this position the pressure of the roller *N'* causes the lever *I* to swing back to the normal position 60 65

70 illustrated in Fig. 1, with a quick positive movement, which, by its momentum and the tension of spring *O*, causes a forcible re-engagement of the contact arm *f* with the terminal *f'*.

75 While I have shown and described my invention as employed in connection with an electric motor, I do not intend to limit the scope of my claims to the use of any specific type of motor, nor to the use of any specific motor controlling member, such as the switch bar *F*. Neither do I intend by the specific description of the mechanism illustrated, including the connections for 80 actuating the switch bar *F* or controlling member, to limit the scope of my invention so as to exclude any mechanical equivalents for the parts shown and described, the terms and expressions herein used and employed in the appended claims being used 85 as terms of description and not of limitation.

90 Having thus described my invention, what I claim as new, and desire to secure by Letters Patent is,—

95 1. A fluid pressure switch mechanism, comprising the combination of a switch supporting lever having a projection angularly faced in two directions from an apiced extremity, an actuating lever controlled as to operation by fluid under pressure, a resilient yielding operating member carried by the actuating lever in a position to move along the angular faces of said apiced extremity and to be forced 100 across said extremity by the actuating lever, and a projection on the actuating lever adapted to engage and actuate the switch supporting lever in one direction at a predetermined stage of actuating lever movement, independently of said operating member.

105 2. A fluid pressure switch mechanism, comprising the combination of a switch supporting lever provided with a fulcrum 110 intermediate of its ends and having an angularly faced apiced projection on one side of said fulcrum, an actuating lever provided with a foot piece adapted to engage the switch supporting lever on the other side of said fulcrum, an operating member pivoted to the actuating lever and adapted to move along the angular faces of said apiced projection to points above and below the apex, and means for resiliently 115 pressing said operating member against said angular faces and in the direction of the longitudinal axis of the switch supporting lever.

120 125 3. A switch mechanism, comprising the combination of a switch supporting lever provided with a tapered extremity, an actuating lever having a projection adapted to engage and positively actuate the switch supporting lever in one direction, a switch 130

operating member yieldingly connected with the actuating lever and adapted to move across said tapered extremity to positions above and below the same, said operating member being adapted to bear yieldingly against the switch supporting lever both when above and when below said extremity, whereby said switch supporting le-

ver may be actuated in two directions by the pressure of said operating member. 10

In testimony whereof I affix my signature in the presence of two witnesses.

JOHN T. JANETTE.
